CONTROL DEVICE FOR HEATING APPLIANCES

Elmer Ellsworth Chandler, Chicago, Ill.

Application May 27, 1935, Serial No. 23,549

2 Claims. (Cl. 137—153)

My invention particularly relates to control devices for heating appliances which use gas as a fuel, the invention being designed to prevent the escape of gas, when the gas pressure in the main again rises after it has fallen so low as to cause the flame to die out. Generally speaking, my improved control device consists in means for preventing the opening of the valve, controlling the passage of gas from the main to the appliance, by an increased gas pressure, after the valve has once closed incident to a dropping of the pressure below a predetermined minimum.

My improved control device is applicable to many forms of heating appliances which utilize gases as fuel, such as gas stoves, appliances for heating water, radiant heaters, etc.

The annexed drawing and the following description set forth in detail certain means exemplifying my improved control device for heating appliances, such means constituting, however, but one of various forms in which the principle of my improved control device may be embodied.

In said annexed drawing:

Figure 1 is a vertical axial section through my improved control device, showing the valve closed;

Figure 2 is a vertical axial section through my improved control device, showing the valve open;

Figure 3 is a plan section, taken in the plane indicated by the line 3—3, Figure 1; and

Figures 4, 5, and 6 are, respectively, a plan view, a side elevation, and an end elevation, of a latch element forming part of my improved control device.

Referring to the annexed drawing in which the same parts are indicated by the same respective numbers in the several views, complementary casing members 1 and 2 are secured together by screws 25 to form an inclosed chamber communicating with an entrance from the gas main formed in an outwardly-extending tapped boss 3, and a discharge port to the heating appliance formed in an outwardly-extended tapped boss 4. The boss 3 also projects inwardly of the casing member 1 and is formed with a valve seat 5 adapted to cooperate with the face of a valve 6 having an upwardly-extended stem 7 which passes through and reaches substantially to the top of, or slightly above the top of, an outwardly-extended tubular boss 16 formed upon the casing member 2 opposite to that side of the chamber upon which the boss 3 is located. The stem 7 is supported by a flexible diaphragm 8 made of silk or other suitable fibrous material which is substantially impervious to the passage of gas, and secured at its edge between the opposed surfaces

of the casing members 1 and 2, the stem 7 being adjustably secured to the diaphragm 8 by nuts 9 and 10, intermediate washers 11 and 12 being provided, the upper part of the stem 7 being exteriorly threaded for engagement with the nuts 9 and 10.

Engaging with the exteriorly-threaded portion of the stem 7, and within the confines of the boss 16, is a nut 21 which forms an adjustable abutment for a latch 18 which is pivoted on pins 19 secured in and projecting from oppositely-disposed upstanding ears 29 formed on the top of the boss 16. The latch 18 is of substantially horse-shoe shape in plan view, Figure 4, and is pivotally mounted adjacent the upper ends of 15 the two side arms of the horse-shoe so that it can swing down into substantially vertical position and for substantially its full length and, when in this position, is adapted to seat by its lower edge upon the abutment 21 so as to prevent the 20 abutment 21 and, hence, the stem 7 and the valve 6 from being raised. In the working of my control device, a tendency of the valve 6 and stem 7 and abutment 21 to rise would be caused by the pressure of gas from the main through the 25 port 3. The purpose of preventing such an opening of the valve by the gas pressure will be hereinafter fully explained. In order to provide for movement of the horse-shoe shaped latch 18 by the wall of the boss 16, the latter is cut away, as 30 indicated by "24", Figures 1 and 2, upon that side adjacent which the latch 18 pivotally moves.

The latch 18 can be swung upon its pivots 19 to release the abutment 21 by manual manipulation and, for this purpose, I form upon one of 35 the sides of the horse-shoe latch an upwardly-extending finger piece 22 which is readily accessible, when a cap 17 is removed, as clearly seen in Figures 1 and 2. However, the extent of manual manipulation of the latch 18 is limited by 40 reason of the fact that that ear 20, which is upon that side of the casing adjacent to the finger piece 22, is formed with a stop member 23 which intercepts the finger piece 22 after the latch 18 has been manually turned on its pivot 19 a pre- 45 determined distance. The purpose in so limiting the manual release movement of the latch 18 is to prevent the same from being thrown over so far as to interfere with, or possibly prevent, the working of an automatic locking function which 50 it possesses and which will be hereinafter fully described.

I provide a tapped boss 13 laterally extended from casing member 2 above the diaphragm 8, which has a port 15 communicating with the 55

casing chamber above the diaphragm 8, and is adapted for the reception of an exteriorly-threaded end of a suitable vent pipe 14. The port 15 and pipe 14 provide means for venting any gas which may pass through the diaphragm 8 and for relieving the pressure above the diaphragm 8.

The operation of the improved control device which has been described is as follows: Assuming that the elements are in the closed position shown in Figure 1, if it is desired to pass gas to the heating appliance, the cap 17 which engages an exteriorly-threaded portion of the boss 16 is removed, and the latch 18 is manually manipulated to lift the same from the abutment 21, whereupon, assuming the gas pressure in the main is equal to, or greater than, a predetermined minimum, such pressure will lift the valve 6 from the seat 5 and pass gas from the port 3 to the port 4 and thence to the appliance. The hand piece 22 is then released and the latch 18 will turn on its pivots 19 by gravity to a position wherein it is rested upon the abutment 21, as clearly shown in Figure 2. Then the cap 17 is replaced. Then any gas pressure equal to or above a certain predetermined minimum will hold the valve 6 open against the weight of the latch 18 and against the weight of the valve stem 7 and associated elements, these weights having been selected suitably for the purpose. These selected weights are such that gas will be passed, under these conditions, suitably for maintaining the fire in the appliance. However, if the gas pressure falls so low as to cause the flame in the heating appliance to go out, such gas pressure is insufficient to hold the valve 6 open against the weight of the latch 18 and of the valve and associated parts, thus resulting in a pressing of the valve 6 tightly to its seat 5 through the medium of the abutment 21 and the weight of the valve parts. Such a closed arrangement of the several elements is shown in Figure 1. This arrangement is such that the latch 18 locks the abutment 21 and thus holds the valve 6 in tightly closed position and any subsequent increase of the gas pressure cannot open the valve 6 against the resistance of the latch 18 bearing upon the abutment 21. Thus, gas will not be further passed into the heating appliance and, therefore, there will not be an accumulation of unburned gases in the appliance due to the gas going out from falling pressure and thereafter

being passed into the appliance by reason of rising pressure. Furthermore, a dropping in gas pressure below the diaphragm 8 sufficient to allow the weight of the latch 18 and valve and associated parts to close the valve, such as a break in the line leading to the appliance, or material leaking in such line, will result in locking the valve 6 shut against the pressure of the gas from the main.

What I claim is:

1. The combination with control device for heating appliances comprising a casing having entrance and exit ports, a valve in the casing controlling the entrance port, the valve being movable to an open position by gas pressure at the entrance port above a predetermined minimum, movable means automatically closing said valve when the gas pressure falls below said minimum, said movable means including a member supported by and movable on the casing and automatically locking the valve in closed position, and manually manipulative means for unlocking said valve locking means and restoring the latter to valve-releasing position, of means limiting the extent of movement in the valve-releasing direction of said locking means attributable to the manually manipulative means, and a cap removably engageable with the casing and rendering the manually manipulative means inaccessible, when in position.

2. The combination with control device for heating appliances comprising a casing having entrance and exit ports, a valve in the casing for the entrance port, a valve stem having an externally-threaded outer end portion, a flexible diaphragm supported by the casing and through which the valve stem extends and by which it is supported, and an adjustable abutment engaging the outer end portion of the valve stem, of oppositely disposed ears extended outwardly from the casing upon the two sides of said stem end, a latch pivotally mounted between said ears and bearing upon said abutment in one direction of pivotal movement to lock the abutment, a manually-engageable member on the latch for swinging the latter on its pivot, and means on said ears for limiting the amount of pivotal movement of the latch in the opposite direction of pivotal movement.
